UNITED STATES PATENT OFFICE.

PIUS BANNER, OF GRANTS PASS, OREGON.

BUTTON-ATTACHING MACHINE.

1,093,582.

Specification of Letters Patent. Patented Apr. 14, 1914.

Application filed March 2, 1911. Serial No. 611,866.

To all whom it may concern:

Be it known that I, PIUS BANNER, citizen of the United States, residing at Grants Pass, in the county of Josephine and State of Oregon, have invented certain new and useful Improvements in Button-Attaching Machines, of which the following is a specification.

This invention relates to improvements in machines for attaching buttons, and has for its object to provide a machine of this class in which the buttons shall be automatically fed from a slotted tube, by means of which they shall be conveyed to and held in the desired position while wire is being threaded through the eye of each successive button, to provide means for automatically paying off wire for each successive staple, by which the wire shall be severed and formed into staples, and by which the said staples shall be driven through the material or fabric to which the buttons are to be attached and clenched.

A further object is to produce a staple, the wire of which shall present flat surfaces opposed to each other in the positions which bind upon the fabric to which it is attached.

The invention consists of the improved construction, arrangement, and combination of parts, which will be hereinafter fully described and particularly pointed out in the claims.

Referring to the drawings, Figure 1 is a top view of the machine with the cover removed, showing a button ready to be attached. Fig. 2 is the same showing button attached. Fig. 3 is a detail view of a plunger, in perspective. Fig. 4 is a lower end view of Fig. 3. Fig. 5 is an end view of the staple holder. Fig. 6 is a perspective view of the staple holder in detail. Fig. 7 is a detail view of a retarding link. Fig. 8 is a detail view of a swinging stop. Fig. 9 is a perspective view of the wire feed lever. Fig. 10 is a detail view of a wire-grip. Fig. 11 is a detail view of a wire holder. Fig. 12 shows a staple in various stages of formation. Fig. 13 is a staple former in operative position. Fig. 14 shows the staple former in inoperative position. Fig. 15 is a detail view of a spring holder, 101. Fig. 16 is an end view of the button feed tube. Fig. 17 is a detail elevation of lower end of button feeding tube. Fig. 18 is a side elevation of my improved machine. Fig. 19 is a side ele-

vation of the stand. Fig. 20 is a top view of the stand. Fig. 21 is a partial top view of the machine. Fig. 22 shows a detail of the wire reel.

Similar characters of reference indicate similar parts in each of the several views.

In the drawings, 3 represents a casing having a floor 6, mounted on supports 103 and 107, which are rigidly attached to base 109, having an aperture 110. The said casing is inclined toward the front, as shown in Fig. 18. The lower or front portion of the bottom 6 is raised slightly as at 40, to afford a track for the wire 41, coming from the wire support 123, which is attached to casing 3 by means of arm 125, the wire being enclosed between upper and lower disks, 120 and 127, which are separated by stays 119, all of which are held in place by cotter pin 124.

The plunger 34 is slidably mounted within the casing, shown in Figs. 1 and 2, and is provided with a depending lug 56, which operates within slot 84 in the floor 6.

Pivotedly mounted on pin 98 in the lug 56 is a drive link 97 which is pivotally connected to bell crank 104 by means of pin 96. Said bell crank 104 is pivotally mounted on pin 105 secured upon support 103.

At the upper end of casing 3 is secured an overhanging arm 85, provided with an orifice 100, in which is secured the spring holder 101, which is adapted to retain springs 102, which are attached by their opposite ends to a similar spring holder 101, held within orifice 99, in bell crank 104. Said springs are adapted to retain plunger 34, at the upper end of the casing in normal position. The operating rod 111 passes through the orifice 110 in the base 109, having the head 108 pivotally connected to the bell crank 104, by means of pin 106.

By applying force downward upon rod 111, bell crank 104 is rocked on its pivot 105, thereby transmitting its motion through link 97 to the plunger 34, forcing it downward to the position shown in Figs. 2 and 18.

Plunger 34 is provided with lateral projections 7 and 29 which form bearings for rod 8 on which is secured the spring retainer 22, adapted to hold spring 13, which abuts against washer 12 forcing rod 8 to the position shown in Fig. 1.

The plunger is cut away forming the notch 16, and the lower side of the body 110

thereof adjacent the notch is rounded so as to form the cam surface 61. The upper face of the plunger also is cut away at 4 on the side opposite the notch 16 to form 5 the cam surface 5. The lower end of the plunger is slotted at 36 to receive the eye of the button 1, and is further provided with notches 66 adapted to form the desired shape of head on the staple 54. On 10 the lateral faces of the lower end of the plunger are formed ribs 65.

Staple holder 2 is slidably held within slot 37 formed in the casing 3, and is provided with the large longitudinal groove 15 68 to receive the lower end of plunger 34, and provided with grooves 70 adapted to receive said ribs 65 of the plunger. Pin 69 held within the upper end of the holder 2, is adapted to pass transversely through slot 20 64 of the plunger, thus causing a limited movement of the holder during each reciprocation of the plunger.

Upon a lateral face of the holder, at its lower extremity, is detachably secured a cutting blade 38, which is held within a notch 25 formed therein, in any usual manner. A similar blade 44 is secured in the side of the groove 37, at a point to bear against the blade 38, as it reciprocates.

Along 30 side of the plunger, is pivotally mounted the wire feed-lever 10, upon the pivot pin 9, engaging aperture 57. Flush with the upper face thereof is the cam engaging projection 15, which is undercut at 35 14. On the lower face of the wire feed-lever 10 is a downwardly projecting pin 33 working in slot 28 in the floor 6, thereby the lateral movement of the lever is limited. This feed-lever is held approximately 40 parallel with plunger 34 by means of spring 27 surrounding pin 23 abutting at one end against washer 26, which is held in place by lug 18 at the inner face edge of case 3, the other end bearing against the lever 10 to 45 which the pin 23 is pivotally attached in the slot 24 upon the pin 25, secured in orifice 63. The outer end of the pin 23 passes through the lug 18 and casing 3, when the lever is swung out by the action of cam 50 5 against the point 15.

At the lower end of lever 10, is hingedly secured the wire-grip 46 by means of a pin 39, engaged in orifice 59. The under side of the wire-grip is provided with a serrated 55 surface 46^a, to engage the wire 41, and it is yieldingly held in engagement therewith by the spring 47, secured upon lever 10.

Wire holder 45 attached to the floor 6 has 60 formed on its under side a serrated surface similar to that of the wire-grip, the serrations being inclined so as to permit a forward movement of the wire and at the same time prevent its retraction. This holder is 65 formed of resilient material and is of the required strength to hold the wire in place.

In order to afford sufficient force to cause the staple holder 2 to sever the wire 41 when engaged by blades 38 and 44, a swinging stop 31^a is pivotally mounted on plunger 34, by means of pin 21 in the orifice 62, and is adapted to abut against the adjacent end of staple holder 2, thus affording a positive connection between the plunger and the holder 2. In order to remove this positive connection, for a purpose hereinafter specified, a retarding link 20 is pivotally secured 75 to projection 31 of stop 31^a by means of pin 32 in said projection which is held within slot 58 of the head 60. At the upper end of said link is formed a slot 17 80 engaging pin 19 in the floor 6. This slot 17 allows a limited movement of plunger 34 and staple holder 2. When the upper end thereof contacts with pin 19 it arrests the downward movement of the retarding link 20 and thereby causing the lower end of stop 31^a to swing outward and away from the upper end of staple holder 2, thus allowing plunger 34, to move within the holder 2, which previous to this time had moved 90 with it.

A staple former 42 is pivotally mounted upon pin 71 attached to the floor 6, the rear end of said staple former being curved upwardly at 52 so as to engage cam surface 61 95 of the plunger 34. The upper face of staple former 42 is recessed at 67, to receive a segment 54^a of wire 41 to form a staple, the forward side of said recess being beveled so that when the wire is forced down upon it, 100 it will assume the shape shown in 54^a. The holder is beveled at 128 to contact with cam surface 129 to force the former out of the line of movement of the plunger.

Upon the front support 107 is formed the 105 upwardly projecting anvil arm 43 carrying on its upper end anvil 51, attached by means of screws 55, which is preferably formed of hardened steel. The anvil is provided upon its face with a transverse groove 49, divided into two parts by the longitudinal central rib 50 and closed at the outer ends by projections 48.

A cover 83 is attached to the case 3 by means of screws held within apertures 11. 115 The forward portion of the cover is beveled at 93 and provided with a slot 126, wherein the eye of the button 1^a is caused to slide until it reaches its intended position. A button-chute 72 having attached on its lower surface at 82, a support 87, is removably held within a socket 89. Said feeding tube is provided along its lower side with a slot 78, to receive the eyes of buttons 1^a. At each side of the lower end of said tube, are 125 formed slots within which stand the free ends of spring 78, secured upon the exterior of the tube; the purpose thereof being to arrest the buttons until ready to be selected for use. A slot 79 also is provided 130

in the upper surface of tube 72, the resulting prongs being bent inward as at 80, to further assist in arresting the buttons.

- Upon the cover 83 is pivotally mounted 5 by means of screw 30^a held within lug 86, a bell crank 76, having in its horizontal arm 94, a slot 95 adapted to engage screw 30 which passes through a slot 35 in the case 3 and is held in projection 29 of plunger 34. 10 At the upper end of this bell crank is pivotally attached by means of pin 75, a feed bar 91 having secured near its lower end, a laterally projecting pin 81, adapted to be held against the upper surface of cam 92 by 15 means of spring 77. A spring 88 attached to the cover 83 by screw 90 and to the upper arm of the bell crank 76, normally holds the latter in a forward position.

This machine may be attached to a bench 20 if desired, though I have shown it in use upon a stand 114 which is provided with a recess 116 adapted to receive the base 109, and which is further provided with button pockets 113 and tube pocket 112. The stand 25 114 is mounted upon a hollow support 115 having the legs 117.

To one of the legs at 121 is pivotally secured foot lever 118, which pivotally is attached at 122 to the operating rod 111, connecting with bell crank 104.

The button feeding tube having previously been filled with buttons and the wire brought from the reel through the casing 3, under the wire-grip 46 and wire holder 45, 35 through the eye of button 1 shown in position in Fig. 1, and the fabric 53 to which the button is to be attached being in place on the anvil, the operation of the machine is as follows: Power is applied to bell crank 40 104 through operating rod 111, by means of foot lever 118. The motion thereof is transmitted through link 97 to the plunger 34; and as it passes downward, cam 5 contacts with point 15 of the wire feed-lever 10 45 throwing it outward against the spring 27, the wire holder 45 preventing the retraction of the wire. This movement also causes screw 30 to operate bell crank 76 causing it to assume the position shown in Fig. 18, 50 where it is in position to force another button forward in the succeeding operation. As the plunger 34 continues downward the swinging stop 31^a forces the staple holder against the wire, causing it to sever a segment 54^a and force it against the staple former 42, so as to form the staple 54^b which is held within slot 70 in the staple holder 2. At this point the stop 31^a is forced to swing 55 outward by the retarding link 20, in the manner above described, thus allowing the pin 8 to come in yielding contact with holder 2, thus forcing the latter against the fabric as shown in Fig. 18. At this point cam surface 61 has moved along the staple former 60 sufficiently to permit the latter to rock on

its shaft 71, so that the head 42 will drop out of the line of movement of the plunger. The plunger continuing its downward movement, drives the staple 54^b through the fabric 53, and the ends of the staple striking 70 the inwardly inclined projections 48, follow the groove 49 until they reach the rib 50, and the further movement of the plunger causes the top to settle leaving the staple formed as indicated at 54. It will be observed that the wire is half round in cross section as shown at 41, Fig. 12, and as it enters the casing it does so through a corresponding aperture which holds it in such position that the staple will always be 75 formed with the flat side inward. The foot lever being released springs 102 cause the bell crank 104 to force the plunger 34 back to its normal position. In its upward movement the lower end of slot 64 engages pin 69 carrying with it the holder 2. As soon as the holder has receded sufficiently to permit the return of the staple former, the cam 61, contacts with the projection 52, rocking the staple former on its pivot and bringing it 80 into position again. During the return movement of the plunger 34, bell crank 76 is rocked forward on its pivot 30^a causing the feed bar 91 to force another button into 85 position ready to receive the end of wire 41, after which the cam 5 will have receded from the projection 15, thereby releasing the lever 10 and allowing it to swing forward, the grip at its end carrying the wire through the eye of the button to the position shown 90 in Fig. 1 ready to attach another button. 95

Having thus described my invention what I claim as new and desire to secure by Letters Patent, is:

1. In a button attaching machine, a frame work,—a casing having a longitudinal slot in its floor secured thereon,—a plunger in the casing having a depending lug adapted to reciprocate in said slot,—a detachable button-chute having a vertical slot at its 105 lower end mounted upon the casing,—a bell crank having a longitudinal slot in its lower arm mounted on said casing,—a feed bar pivotally secured by one end to the upper arm of said bell crank, the lower end reciprocating in the slot of said chute, a guide-pin extending from the plunger through said casing and engaged in the slot of said bell crank,—and means for reciprocating the plunger whereby the feed bar is 110 115 operated.

2. A button attaching machine comprising a casing, a staple-former consisting of a bar pivotally mounted in the casing and having a staple-forming projection at its 120 lower end,—a plunger mounted to reciprocate above said bar,—a staple-holder slidably held at the lower end of the plunger and adapted to embrace said projection,—a stop pivotally connected to said plunger and 125 130

bearing against the staple-holder, upon which stop is formed a lateral projection,— a stud mounted in the base of the casing,— a retainer having a slot in its upper end adapted to slide upon said stud and pivotally connected to said lateral projection, whereby the stop is swung from engagement with the staple-holder, which permits the plunger to descend within the staple-holder.

- 10 3. In a button attaching machine a casing, a bar pivoted at an intermediate point therein, a staple former formed in the face of said bar at its lower end, a plunger mounted to reciprocate above said bar, a staple holder 15 slidably mounted on the lower end of said plunger and adapted to embrace said staple former, a stop pivotally secured to the plunger and bearing on the staple holder for driving it forward, a link having limited 20 longitudinal movement pivotally secured in the casing and connected to said stop whereby the latter is withdrawn from the holder during the advance of the plunger, means for preventing recoil of the holder, means 25 for reciprocating the plunger, and means on the plunger for rocking the bar on its pivot whereby the staple former is brought into line with the staple holder during its upward stroke and withdrawn from the path of the 30 plunger during its downward stroke.

4. In a button attaching machine, a casing having a bottom formed on an inclined plane with a longitudinal slot therein, a plunger adapted to reciprocate upon the 35 bottom of said casing, a lug depending from the plunger through said bottom slot, a button chute having a slot in its lower end mounted above the casing, a bell-crank lever having a slot in its lower arm pivotally 40 mounted on the casing above the line of movement of the plunger, a feed-bar pivoted to the upper end of said bell-crank, the lower end reciprocating in the slot of the button chute, a pin extending laterally from the 45 plunger through the slot in said bell-crank, and means connected to said depending lug for operating the plunger.

5. In a button attaching machine, a casing

having a bottom formed on an inclined plane with a longitudinal slot therein and a slot 50 in the side member adjacent thereto, a plunger adapted to reciprocate on the bottom of said casing, a lug depending from the plunger through the bottom slot, a button chute having a slot in its lower end mounted above 55 the casing, a bell-crank lever having a slot in its lower arm pivotally mounted on the casing above the line of movement of the plunger, a feed-bar pivoted to the upper end of the bell-crank, the lower end reciprocating in the slot of the button chute, a pin 60 extending laterally from the plunger through said lateral slot and the slot in said bell-crank, a bell-crank pivoted to the framework below said casing, a spring for holding 65 the last named bell-crank normally at its upper limit, a link connecting said bell-crank with said depending lug, and means for depressing it for operating said plunger.

6. In a button attaching machine, a casing having a bottom formed on an inclined plane with a longitudinal slot therein and a slot in the side member adjacent thereto, a plunger having a transverse slot in its lower portion adapted to reciprocate on the bottom of said casing, a lug depending from the plunger through said bottom slot, a button chute having a slot in its lower end mounted above the casing, a bell-crank lever 70 having a slot in its lower arm pivotally mounted on the casing above the line of movement of the plunger, a feed-bar pivoted to the upper end of the bell-crank, the lower end reciprocating in the slot of the button chute, a pin extending laterally from the 75 plunger through said lateral slot and the slot in said bell-crank, a staple holder slidably mounted in the slot in the lower portion of the plunger, and means connected to said depending lug for operating the plunger. 80

In testimony whereof I affix my signature in presence of two witnesses.
